US00D947629S

(12) **United States Design Patent** (10) **Patent No.:** **US D947,629 S**
Blay (45) **Date of Patent:** **** Apr. 5, 2022**

(54) **ELECTRONIC TORQUE WRENCH**

(71) Applicant: **M3 HEALTH INDÚSTRIA E COMÉRCIO DE PRODUTOS MÉDICOS, ODONTOLÓGICOS E CORRELATOS S.A.**, Jundiaí (BR)

(72) Inventor: **Alberto Blay**, São Paulo (BR)

(73) Assignee: **M3 HEALTH INDÚSTRIA E COMÉRCIO DE PRODUTOS MÉDICOS, ODONTOLÓGICOS E CORRELATOS S.A.**, Jundiaí (BR)

(**) Term: **15 Years**

(21) Appl. No.: **29/722,618**

(22) Filed: **Jan. 31, 2020**

(30) **Foreign Application Priority Data**

Aug. 3, 2019 (BR) 30 2019 003535 9

(57) **CLAIM**

The ornamental design for an electronic torque wrench, as shown and described.

DESCRIPTION

FIG. 1 is a perspective view showing the new design for the electronic torque wrench;

FIG. 2 is a front view of the electronic torque wrench of FIG. 1;

FIG. 3 is a back side view of the electronic torque wrench of FIG. 1;

FIG. 4 is a left side view of the electronic torque wrench of FIG. 1;

FIG. 5 is a right side view of the electronic torque wrench of FIG. 1;

FIG. 6 is a top view of the electronic torque wrench; and, FIG. 7 is a bottom view of the electronic torque wrench of FIG. 1.

1 Claim, 7 Drawing Sheets
